PORTABLE SERVING UNIT

William J. Gribbens, St. Paul, Minn., assignor to Plastics,
Inc., St. Paul, Minn., a corporation of Minnesota

Filed Jan. 27, 1964, Ser. No. 78,367

Term of patent 14 years

(Cl. D14—3)

FIG. 1

FIGURE 3 is a perspective view of one portion of the unit with the shelf members omitted and the oppositely disposed portion being detached therefrom for convenience of illustration.

The end of the unit opposite that shown in FIGURE 1 is the same as the end illustrated, and the rear side of the unit is the same in appearance as that illustrated in FIGURES 1 and 2.

The broken lines are shown for illustrative purposes only.

I claim:

The ornamental design for a portable serving unit, as shown and described.
